UNITED STATES PATENT OFFICE.

ZELIA NUTTALL, OF DRESDEN, GERMANY.

DESIGN FOR A TABLE.

SPECIFICATION forming part of Design No. 21,802, dated August 30, 1892.

Application filed August 5, 1892. Serial No. 442,283. Term of patent 3½ years.

To all whom it may concern:

Be it known that I, ZELIA NUTTALL, a citizen of the United States, now residing in Dresden, Germany, have invented and produced 5 a new and original Design for Stools, Tables, &c., of which the following is a specification, reference being had to the accompanying drawing.

The drawing represents in perspective a 10 stool or low table embodying my design.

The leading features of my design consist in the peculiar angular configuration given 15 the legs or portions below the body, as shown in the drawing, together with a border or plain edging extending around both the body and leg portions.

A stool, table, or similar structure embodying my design presents to the eye an angular body A, with supporting portions B, having

somewhat the appearance of a Greek fret, the 20 characteristic effect being due to the straight sections b, joined at an angle or cut to appear to be so joined and together going to make up the supports and sides of the structure below the body A. Along the edges of the 25 structure is arranged a plain edging D, which follows and lies parallel with the said edge. This edging has sharp corners and presents the appearance of a bead square in cross-section. 30

What I claim is—

The design for a table, stool, or similar article, substantially as herein shown and described.

ZELIA NUTTALL.
